UNITED STATES PATENT OFFICE.

HENRY B. BURNS, OF EAU CLAIRE, WISCONSIN, ASSIGNOR OF ONE-FOURTH
TO EDSEY A. MUNNS, OF EAU CLAIRE, WISCONSIN.

FRUIT-JAR.

SPECIFICATION forming part of Letters Patent No. 702,702, dated June 17, 1902.

Application filed October 31, 1901. Serial No. 80,686. (No model.)

To all whom it may concern:

Be it known that I, HENRY B. BURNS, a citizen of the United States, and a resident of Eau Claire, in the county of Eau Claire and 5 State of Wisconsin, have invented certain Improvements in Fruit-Jars, of which the following is a specification.

This invention is an improvement in fruit-jars; and the object of the invention is to 10 provide a simple and effective closure which will hermetically seal the contents of the jar and in which the top and sealing devices are of such construction that the jar can be readily and conveniently sealed.

15 The following specification enters into a detail description of my invention, reference being had to the accompanying drawings, and to letters thereon which designate the different parts, and what I claim in the particular 20 construction and combination is more specifically set forth in the appended claim.

In the drawings, Figure 1 is a side elevation of a fruit-jar constructed in accordance with my invention. Fig. 2 is a similar view 25 with the parts of the jar separated. Fig. 3 is a view with the top or cover elevated. Fig. 4 is a vertical sectional view through the jar. Fig. 5 is a detail view.

Referring to said drawings, A designates 30 the jar, which is of the usual shape and has a short neck a. The outer surface of the neck a is perfectly plain and smooth, while 35 interiorly said neck is provided with L-shape grooves or recesses a', by which the top is temporarily locked in place, as hereinafter described.

B designates the top or cover for the jar, the lower portion b of which is of such size as to fit snugly within the neck a, while the upper portion is formed with a projecting flange b', which provides an inclined shoulder b'', that is adapted to rest upon the inclined upper edge of the neck of the jar. The flange projects sufficiently to bring the outer surface thereof flush with the outer surface of the neck a, so that an even joint is provided to receive the rubber band C, the said rubber band being adapted to tightly close said joint. The lower portion b of the top B is provided 45 with projecting lugs b'', adapted to engage the L-shape recesses hereinbefore referred to,

and said lower portion is also provided peripherally with a number of vertical grooves b', extending from near the lower edge thereof and terminating near the shoulder b''. 55 These grooves form an important feature of the invention, for in applying the top the said grooves are filled with the juices or syrup and effectually exclude the air from the contents of the jar. In connection with the grooves 60 the under side of the top is convex, as shown, so that no air-bubbles will be confined in the jar.

When the top is applied to the jar, the joint between the flange b' and neck of the jar is 65 tightly sealed by means of the rubber band C, which is placed over the joint, and this rubber band is pressed firmly against the joint to hermetically seal the same by means of a metal tightening-band D, which is placed 70 over said rubber band and drawn tightly around the same. This tightening-band is drawn around the rubber band by means of a bolt and nut e and e', respectively, which engage the ends of said band, and the particular connection of these parts is such that no soldering or riveting is required. In carrying out this part of the invention one end of the metal band D is bent at right angles, as shown at d, and upon the other end is 75 formed a projection d' a short distance from the terminus, the said projections d and d' being pierced to receive the bolt. The projection d' is formed by bending the band outward and inward, as shown, and the terminal portion d'' is adapted to lie under the other end of the band, so that it may ride thereon and prevent the rubber band from 80 puckering up between the ends of the tightening band or clamp. It will be noted that 85 the nut e' and head of the bolt e bear against the projections d and d' of the tightening band or clamp and that by turning the bolt the ends of said tightening-band are brought together; also, that a flat side of the nut bears 90 against the metal band, so that it will be held and permit the parts to be tightened by merely turning the bolt; also, that the head of the bolt is grooved, so that it may be turned by a screw-driver or case-knife. 95

Having thus described my invention, the operation of the same will be readily under-

stood from the foregoing, in connection with the accompanying drawings, for after filling the jar the top is placed on with the lugs b^3 in engagement with the L-shape recesses in 5 the neck to temporarily lock said top in place. The rubber band is then placed over the joint between the top and neck, and the tightening band or clamp placed over the rubber band and tightened thereon by turning the 10 bolt. The jar is then effectually sealed, and to prevent working of the contents care should be taken to have the jar filled, so that the syrup or juice will be pressed into the 15 grooves b^4 of the top.

15 The improved sealing devices for fruit-jars constructed as herein shown and described not only provide for hermetically sealing the contents of the jar, but also serve to firmly hold the top in place, as the lugs thereon engage 20 grooves in the neck to prevent upward movement, while the tightening band or clamp serves to hold the top in such engagement and also presses the band against the joint.

Having thus described my invention, I do 25 not wish to be limited in my protection by

patent to what is herein particularly shown and described, for it is obvious that immaterial changes or modifications could be made within the scope of my claim without affecting any of the advantages of the invention. 30

I claim—

In a fruit-jar, the combination with the neck having L-shape recesses in the inner side thereof, a top or cover having a portion which fits within the neck of the jar and provided with a flange which rests upon the neck and also provided with lugs adapted to engage the aforesaid recesses, said lower portion provided with grooves extending from the lower edge thereof upward; of a rubber 40 band placed over the joint between the top and neck, and a clamping-band placed over the rubber band, substantially as shown, the under side of the top or cover being convex.

In testimony whereof I affix my signature 45 in the presence of two witnesses.

HENRY B. BURNS.
